CLAIM

The ornamental design for a respirator, as shown and described herein.

DESCRIPTION

FIG. 1 is a front, right perspective view of a respirator.

FIG. 2 is a front elevation view of the respirator.

FIG. 3 is a rear elevation view of the respirator.

FIG. 4 is a left side elevation view of the respirator.

FIG. 5 is right side elevation view of the respirator.

FIG. 6 is a top plan view of the respirator; and,

FIG. 7 is a bottom plan view of the respirator.

In the drawings, the equal-length broken lines depict portions of the respirator that form no part of the claimed design.

1 Claim, 7 Drawing Sheets
